UNITED STATES PATENT OFFICE.

SIMON MYERSON, OF CAMBRIDGE, MASSACHUSETTS.

ARTIFICIAL TOOTH.

Application filed March 5, 1925. Serial No. 13,108.

This invention relates to an artificial denture including an artificial tooth having a recess in its base and a molded vulcanite or other plate, to which the tooth is attached, 5 by a portion of the plate material entering the recess.

The invention is embodied in the improvements hereinafter described and claimed, in the tooth element of a denture characterized 10 as above stated.

Of the accompanying drawings forming a part of this specification,—

Figure 1 is an edge view, on an enlarged scale, of a tooth embodying the invention.

15 Figure 2 is a rear view, looking toward the lingual face.

Figure 3 is a section on line 3—3 of Figure 2.

20 Figure 4 is a view similar to Figure 3, showing a portion of a vulcanite plate to which the tooth is fixed.

The same reference characters indicate the same parts in all of the figures.

25 12 designates the lingual face, and 13 the labial face of a tooth to which my invention relates, these being of any suitable form. The base 14 is preferably of annular form, as shown by Figure 2. The tooth is provided with a substantially conical recess 15, the 30 mouth of which opens upon the base. The wall of the recess tapers from the mouth to the bottom, as indicated by Figures 2 and 3.

35 The recess is adapted to receive a portion 16^a of the material from which a vulcanite plate 16 is formed. The portion 16^a is forced into the recess while the material is plastic, and is formed by the recess wall into an anchoring projection.

40 The portion 15^a of the recess wall nearest the lingual face 12, and called the lingual side of the recess, is inclined inward from the base toward the lingual face, and is also inclined relative to the longitudinal median line of the tooth indicated by the broken line 17 (Figure 3), a prolongation of the inclined wall portion being indicated by the broken line 18. The lingual side 15^a is therefore undercut and interlocked with the projection 16^a as shown by Figure 4.

45 50 The portion 15^b of the recess wall nearest the labial face 13, and called the labial side of the recess, is also inclined inward from the base toward the lingual face 12, and is inclined relative to the lingual side 15^a of the recess, so that the sides 15^a and 15^b converge from the mouth toward the outer

end of the tooth, as shown by Figures 3 and 4. The described form of the recess wall is such that it facilitates the displacement of air from the recess by the plate material 16^a forced into the same, and prevents liability of the pocketing of air in the recess, and the weakening of retention which would be involved by such pocketing. An air vent 21, 60 may extend from the recess to an outer surface of the tooth, although this is not essential in most cases.

A headed anchoring pin 19, similar to that disclosed by my former application, is embedded in the tooth and projects from the 70 labial side 15^b of the recess wall. The projecting portion of the pin is adapted to be embedded in the projection 16^a at a point spaced from the undercut labial side 15^a as shown by Figure 4, so that the projection is 75 retained in contact with the labial side 15^b of the recess by the anchoring pin.

The head 20 of the pin is substantially flush with or below the base 14, as shown by Figures 1 and 3, so that it does not project 80 into the body of the plate 16. The thickness of the portion of the plate body on which the projection 16^a is formed, may, therefore be reduced to a minimum.

I am aware that a crown tooth having a 85 recess in its base, is not new. Heretofore the recess has been of substantially uniform diameter from its mouth to its bottom, or has been slightly larger at the bottom than at the mouth, the form of the recess being such that 90 it is difficult to completely fill the recess with the plate material, and prevent the pocketing of air at the bottom of the recess.

Teeth as heretofore recessed, are therefore 95 liable to be insufficiently retained by the plate material, so that many of such teeth have fallen off. A porcelain tooth is translucent and the labial side of the recess heretofore formed has been in such close proximity to the labial face, that the plate material in the recess is dimly visible on the labial face, and has a discolored effect.

In my construction, the inclined labial side 15^b of the recess provides sufficient thickness between it and the labial face to 100 prevent discoloration, and is arranged to prevent tendency of the recess to retain air in packing. The pin 19 is arranged to perform the function of the abrupt labial side of the recess heretofore used, and provides the necessary retention without interfering with the packing of the plate mate- 110

rial, or without having a tendency to retain air.

I claim:

An artificial tooth having a lingual face, 5 a labial face, a base, a recess whose mouth opens on the base, said recess having a lingual side inclined as a whole inward from the base toward the lingual face of the tooth, and a labial wall that extends con- 10 tinuously from the inner end of said lin-

gual wall to the base of the tooth adjacent the labial face of the tooth, so that said lingual side of the recess is undercut to engage a plate material, and a pin projecting from the labial wall of the recess and having 15 its outer end within the recess.

In testimony whereof I have affixed my signature.

SIMON MYERSON.
